UNITED STATES PATENT OFFICE.

WASHINGTON DANENHOWER, OF KNOXVILLE, TENNESSEE.

TYPE-WASHING MACHINE.

No. 902,862.

Specification of Letters Patent.

Patented Nov. 3, 1908.

Application filed December 16, 1907. Serial No. 406,626.

To all whom it may concern:

Be it known that I, WASHINGTON DANENHOWER, a citizen of the United States, residing at Knoxville, in the county of Knox and State of Tennessee, have invented a new and useful Improvement in Type-Washing Machines, of which the following is a specification, reference being had to the accompanying drawing.

10 My improvement relates to machines for washing printers' type after such type has been used and has taken on accumulations of ink, dust, and other matter.

15 The object of the invention is to provide an apparatus by means of which considerable quantities of such type may be effectively and rapidly cleansed and drained, the different "sorts" of type being kept separate from each other.

20 The present invention is an improvement upon the apparatus made the subject-matter of an application filed by me in the United States Patent Office October 28, 1907, Serial No. 399,424.

25 The present invention adapts the apparatus for evaporation of water adhering to the type and the interior of the cylinder when the latter is raised from the rinsing tank for drainage, in order that the type 30 may not adhere to the inner faces of the cylinder walls or to each other when the washing operation has been completed and it is desired to discharge the type.

In the accompanying drawings, Figure 1 35 is a plan of an apparatus embodying my improvement; Fig. 2 is an end elevation of the same apparatus, a portion being broken away; Fig. 3 is a perspective of the apparatus when folded for storage or shipment.

40 Referring to said drawings, 1 is a tank member constituting the base of the machine, and 2 is a similar hollow member serving as a tank when the apparatus is in use and also as a top for the apparatus when the latter 45 is not in use. Said two members are joined to each other along adjacent free side edges by alternating eye members, 3, located on said two members and a pintle shaft, 4, extending through said eye members. Thus 50 the tank member, 2, may be folded or turned over upon the tank member, 1, so that the two of said members together constitute a box inclosing the cylinder, to be hereinafter described, when the apparatus is not in use. 55 To the side wall of the tank member, 2, which is opposite said hinge there is applied a

slotted hasp, 5, adapted to receive a loop, 6, on the corresponding wall of the tank member, 1, when the member, 2, rests upon said member, 1. By this means, the member, 2, is secured in the closed position upon the member, 1. Each of said tank members, 1 and 2, is provided at one end, and near the bottom, with a faucet, 7, for the discharge of liquids from said members. Said tank members are preferably made of sheet metal of sufficient thickness to bear the weight of the cylinder and the top carried by the cylinder during the washing operation. At the middle of the upper edge of each end wall 70 of the tank members, 1 and 2, is a notch or bearing, 9, preferably half-circular.

C is a hollow cylinder into which the type is placed for the washing operation. Said cylinder comprises an axial shaft, 10, having 75 at one end a crank, 11. In the perimeter of said cylinder are any desired number of doors, 12, opening into compartments for receiving various sorts of type for cleansing. As the structure of said cylinder does not differ from the cylinder of my above-mentioned application, I deem it unnecessary to herein illustrate and describe said cylinder in detail. Portions of the walls of said cylinder are perforated to permit the passage of liquid, said perforations being smaller than the type to be washed.

The operation is as follows: A cleansing solution, for example a solution of lye, is put into one of the tank members, preferably 90 the base member, 1, in order that said solution may be used repeatedly before being discharged from the faucet, 7. A rinsing liquid, such as ordinary clean water, is placed into the other tank member. Unclean type 95 is placed into the cylinder compartments through the ports, 12. The cylinder is then placed into the tank member containing the cleansing solution, the shaft, 10, resting in the bearings, 9. The cylinder is then rotated by turning the crank, 11. Such rotation moves the lower portion of the cylinder, and the type in the lower compartments of the cylinder, through the cleansing liquid. When the cylinder has been rotated a sufficient time for this portion of the operation, the cylinder is lifted out of the liquid and held above said liquid long enough to permit drainage back into said tank member. Then the cylinder is lifted over into the adjoining tank member, the shaft, 10, being placed in the bearings, 9, of that member.

Then the cylinder is similarly rotated until the liquid in said tank member completely rinses the type in the cylinder. Then the cylinder is raised and held over said tank member to permit the rinsing water to drain therefrom. To facilitate the shifting or transferring of the cylinder from one tank member to the other, a connecting bar or arm, 21, is applied to each end of the shaft, 10, and to the adjacent end of the pintle, 4, said bar having at each end a bearing, 22, to receive said shaft and said pintle. The distances between said pintle and the bearings, 9, of the tank members are equal. Hence the cylinder and the connecting arms may be together lifted from one tank member and turned into position on the other, the cylinder axis being carried through half circles of which the connecting arms are radii. A supporting member or prop, 23, is applied to each tank member beneath the bearing, 9. One end of said props is hinged to the end wall of the tank member at 24 while the opposite end of said prop is provided with a notch, 25. When the cylinder is raised for drainage, said prop is turned so as to bring the free end up, and the shaft, 10, is then allowed to descend and rest in said notch. In such position, the cylinder may be left any desired length of time for drainage. A stop, 26, is placed adjacent each prop, 23, to support the latter in the elevated position when the connecting arm, 21, is not used. To permit the ready removal of the cylinder, C, from the apparatus so that it may be carried to a table for filling and emptying, the connecting arms, 21, may be provided with a latch, 27, as shown in the drawings.

D is a hood having a top wall, 28, end walls, 29, and a side wall, 30. Said hood is a little longer than the length of the tank members, in order that it may extend partially over the tank member containing the rinsing liquid, the end walls, 29, lapping partially over the end walls of said tank member when the apparatus is in use, and entirely over the end walls of the two tank members when the apparatus is folded. Each end wall, 29, has a slot, 31, to receive the shaft of the cylinder when the apparatus is folded as shown in Fig. 3, and the end wall, 29, which is to extend over the ends of the tank members having the faucets, 7, has notches, 32, to receive said faucets when the apparatus is folded.

When the apparatus is set for operation and the cylinder is raised into the position shown in Fig. 2 for draining water from the cylinder after rinsing in the adjacent tank member, the hood, D, is put into the position shown in Figs. 1 and 2, the lower edges of the end walls, 29, and the side wall, 30, resting upon the table which supports the two tank members, and the end walls, 29, partially overlapping the ends of the cylinder and the adjacent tank member. Said hood and tank member together form an enclosure from which air may pass through the cylinder and into which air may pass through the slots or notches, 31 and 32, of the end walls, 29, of the hood. A heating lamp or printers' stove, 33, or any other desired form of heater, is placed within the hood. Said heater heats the air within said hood and said heated air moves through the cylinder and evaporates the water adhering to the surfaces of the type and the inner surfaces of the cylinder. Such evaporation eliminates the water which causes type to adhere to the inner faces of the cylinder walls. After a few rotations of the cylinder while said heated air is passing through the cylinder, such drying is accomplished, and the type will then promptly discharge by gravity when an open cylinder compartment is turned down.

I claim as my invention:

1. In an apparatus of the nature described, a tank provided with bearings, a hollow cylinder having journals adapted to rest in said bearings, mechanism for supporting said cylinder above said bearings, and a hood adapted to inclose a space beside said tank and partially cover said cylinder when the latter is in the elevated position, substantially as described.
2. In an apparatus of the nature described, a tank provided with bearings, a hollow cylinder having journals adapted to rest in said bearings, mechanism for supporting said cylinder above said bearings, and a hood adapted to inclose a space beside said tank and partially cover said tank and said cylinder when the latter is in the elevated position, substantially as described.
3. In an apparatus of the nature described, a tank provided with bearings, a hollow cylinder having journals adapted to rest in said bearings, mechanism for supporting said cylinder above said bearings, and a hood adapted to inclose a space beside said tank and partially cover said tank and said cylinder when the latter is in the elevated position, the walls of said hood having openings for the passage of air, substantially as described.
4. In an apparatus of the nature described, two tank members each provided with bearings, a cylinder having journals adapted to rest in the bearings of either of said tank members, mechanism for supporting said cylinder above the bearings of one of said tanks, and a hood adapted to inclose a space beside said tank and partially cover said cylinder in the elevated position and slide over said two tanks when the latter are folded upon each other, substantially as described.
5. In an apparatus of the nature described, two tank members each provided with bearings, a cylinder having journals adapted to rest in the bearings of either of said tank members.

members, mechanism for supporting said cylinder above the bearings of one of said tanks, and a hood adapted to inclose a space beside said tank and partially cover said cylinder in the elevated position and slide over said two tanks when the latter are folded upon each other, said hood having notches in its end walls, substantially as described.

In testimony whereof I have signed my name, in presence of two witnesses, this 12th day of December, in the year one thousand nine hundred and seven.

WASHINGTON DANENHOWER.
